The ornamental design for a transmitter, as shown and described.

DESCRIPTION

FIG. 1 is a perspective view of the transmitter of my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The surface shading on claimed surfaces in all figures show contour and not surface ornamentation. The broken lines and the surfaces adjacent to broken lines without surface shading illustrate portions of the transmitter that form no part of the claimed design.
